ABSORPTION REFRIGERATING APPARATUS

Nils Erland af Kleen, Stockholm, Sweden

Original application July 16, 1937, Serial No. 154,090. Divided and this application November 20, 1940, Serial No. 366,324. In Great Britain July 23, 1936

6 Claims. (Cl. 62—118)

This invention relates to new and useful improvements in absorption and adsorption refrigerating apparatus of the intermittent type including a boiler absorber containing dry salts or other materials capable of absorbing refrigerant in gaseous form during the absorbing phase operation and of expelling such refrigerant during the generating or expulsion phase operation of the unit, the present application being a division of my co-pending application Serial No. 154,090, filed July 16, 1937, covering Absorption and adsorption refrigerating apparatus.

For convenience of reference, the terms "absorption" and "absorber" hereinafter mentioned will be used to include "adsorption" and "adsorber." Similarly, the expression "dry salts" will be used to include other materials capable of absorbing or adsorbing gaseous refrigerant.

Considerable difficulty has been encountered in the operation of refrigerators of the type above mentioned, and I have found that this has been due to the return to the boiler absorber of quantities of the refrigerant in liquid form. When coming into contact with the salts in the boiler absorber, the liquid marbleizes the salts and greatly reduces the effectiveness of such salts for further absorption. Moreover, the liquid expands or swells the salts far beyond their normal expansion produced when absorbing vapor refrigerants, with the result that the walls of the boiler absorber are distorted by such abnormally expanded salts, and leaks develop therein. It therefore becomes necessary to shut down the unit and replace the boiler absorber with a new one containing a fresh charge of dry salts.

One of the primary objects of this invention is to overcome the above noted disadvantages in refrigerating apparatus of this type and to provide means for preventing the feeding back of liquid into the boiler absorber.

The refrigerating unit in absorption systems usually comprises in addition to the boiler absorber, a condenser, and an evaporator, all coupled together and forming a closed system or circuit for the refrigerant. In the normal operation of the unit, heat is applied to the boiler absorber during the generating or expulsion period to drive out the gaseous refrigerant and the latter passes through an outlet pipe to the condenser where it is condensed and the condensate flows to the evaporator. During the absorption period, the refrigerant returns in vapor form from the evaporator to the boiler absorber to be absorbed by the dry salts. However, after the unit has been turned off for any length of time,

or prior to being placed into use, the refrigerant tends to collect in liquid form in the evaporator, and in the event the unit is inverted or tipped over to the side as is frequently the case when transporting the same from place to place, the liquid refrigerant then flows through the connecting pipes into the boiler absorber, especially when the evaporator is located at about the same level or below the level of the boiler absorber.

It is therefore another object of the present invention to provide means for preventing the liquid refrigerant from coming into contact with the absorbent material in the event the unit is accidentally tipped or is inverted.

According to the invention, there is provided in the closed system for the refrigerant a liquid trap or other suitable means interposed either between the condenser and the boiler absorber or between the condenser and the evaporator end of the unit, which will prevent any liquid refrigerant present in the evaporator from flowing back to the boiler absorber and contacting the dry salts therein.

With the above and other objects in view which will appear as the description proceeds, my invention resides in a novel feature hereinafter set forth, illustrated in the accompanying drawing and more particularly pointed out in the appended claims.

Referring to the drawing which illustrates diagrammatically an absorption refrigerating unit including boiler, absorber, condenser, accumulator and evaporator with one form of liquid trap interposed between the condenser and the boiler absorber.

10 designates a boiler absorber in the form of a cylindrical shell in which are disposed a plurality of annular trays 11 containing dry salts or other absorbent material 12. The shell 10 is provided centrally thereof with a flue 13 for heating the boiler absorber, for example, by means of a gas-burner 14. During this heating the refrigerant is expelled from the boiler absorber through line 15, which extends downwardly from the upper portion thereof and terminates in an inverted U-bend 16 in a chamber 17. From this chamber the refrigerant vapors are conducted through line 18 from the bottom of the chamber into a condenser 19, where such vapors are condensed and the condensate delivered to an accumulator or collecting tank 20. An evaporator 21 in the form of a coil leads from the bottom of accumulator 20 and terminates at its opposite end in communication with the upper portion of said accumulator.

A pipe 22, opening in communication with the upper portion of chamber 17, extends upwardly therefrom and terminates in communication with a closed vessel 23. Thus, in the event the unit is tilted or inverted and liquid refrigerant is present in either the accumulator 20, or the evaporator 21, such liquid refrigerant will flow through the condenser 19, pipe 18, chamber 17, pipe 22, and collect in vessel 23. It will of course be understood that the vessel 23 is constructed of such dimension as to be capable of containing the entire refrigerant in its liquid form which circulates in the system.

When the unit is returned to upright or normal position, the liquid refrigerant collected in vessel 23 returns to the evaporator 21 through the pipe 22, chamber 17, pipe 18, condenser 19, and accumulator 20. The operation of the unit is the same as that described in my co-pending application, Serial No. 154,090. As shown in the drawing of the present application, the unit is operating in the expulsion phase and the burner 14 is "on" in order to heat the boiler absorber 11, thereby driving out the refrigerant vapors absorbed by the dry salts 12. The expelled vapors flow through pipe 15 into chamber 17, and from this chamber pass through the condenser 19 where they are condensed and collect in accumulator 20. For the absorption phase period of the unit, the burner 14 is shut down and the boiler absorber 11 is cooled by any suitable means not shown. The refrigerant evaporated in the evaporator 20 then returns in vapor form to the boiler absorber to be absorbed by the dry salts.

While I have shown the liquid trap formed by the chamber 17, pipe 22, and vessel 23, interposed in the connecting pipe 15 between the boiler absorber 11 and the condenser 19, said trap may be interposed in the unit between the condenser 19 and the accumulator 20. Furthermore, while the unit shown in the drawing includes an accumulator 20, in certain units the accumulator may be dispensed with, and in this event the liquid trap may be interposed between the boiler absorber 11 and the condenser 19 as heretofore described, or between the condenser and the evaporator.

From the foregoing it is believed that the advantages and operation of the invention may be readily understood by those skilled in the art without further description, it being borne in mind that changes in the details of construction may be made without in any way departing from the spirit of the invention as set out in the following claims.

What I claim and desire to secure by Letters Patent is:

1. In absorption refrigerating apparatus of the type operating intermittently in the expulsion and absorption phases, respectively, including a closed system for a refrigerant, said system having a plurality of elements arranged to provide a boiler absorber containing dry salts, a condenser, and an evaporator coupled in series to permit the refrigerant to be withdrawn from said evaporator and absorbed by said dry salts during the absorption phase operation of said apparatus, and to be expelled from said boiler absorber and delivered to said evaporator during the expulsion phase operation of said apparatus; means for preventing the return of said refrigerant in liquid form from said evaporator to said boiler absorber, comprising a chamber interposed in said closed system through which the refrigerant flows on its way to the boiler absorber dur-

ing the absorption phase operation, and from the boiler absorber to the evaporator during the expulsion phase operation, and means cooperating with said chamber for receiving liquid refrigerant from said evaporator when the apparatus is tilted from its normal position.

2. In absorption refrigerating apparatus of the type operating intermittently in the expulsion and absorption phases, respectively, including a closed system for a refrigerant, said system having a plurality of elements arranged to provide a boiler absorber containing dry salts, a condenser, and an evaporator coupled in series to permit the refrigerant to be withdrawn from said evaporator and absorbed by said dry salts during the absorption phase operation of said apparatus and to be expelled from said boiler absorber and delivered to said evaporator during the expulsion phase operation of said apparatus; means for preventing the return of said refrigerant in liquid form from said evaporator to said boiler absorber, comprising a closed vessel interposed in said closed system through which the refrigerant flows on its way to the boiler absorber during the absorption phase operation and from the boiler absorber to the evaporator during the expulsion operation, a second closed vessel arranged above said first named vessel, and a pipe connection establishing communication between said vessels, whereby when said apparatus is inverted, the refrigerant liquid flowing from said evaporator is diverted into said second named vessel.

3. Absorption refrigerating apparatus of the type operating intermittently in the expulsion and absorption phases, respectively, comprising a closed system for the circulation of a refrigerant, said closed system including a boiler absorber containing dry salts capable of absorbing refrigerant vapors during the absorption phase operation of the apparatus and of driving out said vapors during the expulsion phase operation of the apparatus, a condenser for condensing the refrigerant vapors driven out during the expulsion phase operation, means connecting said boiler absorber with said condenser, an evaporator for said liquid refrigerant, means connecting said condenser with said evaporator, whereby the condensed refrigerant flows to said evaporator during the expulsion phase operation and the refrigerant evaporated in said evaporator returns to the boiler absorber during the absorption phase operation of the apparatus, and a liquid collecting trap cooperating with said first named connecting means for preventing the return of liquid refrigerant from said evaporator to said boiler absorber when the apparatus is tilted.

4. Absorption refrigerating apparatus of the type operating intermittently in the expulsion and absorption phases, respectively, comprising a closed system for the circulation of a refrigerant, said closed system including a boiler absorber containing dry salts capable of absorbing refrigerant vapors during the absorption phase operation of the apparatus and of driving out said refrigerant vapors during the expulsion phase operation, a condenser for condensing the refrigerant vapors driven out during the absorption phase operation, a chamber disposed between said boiler absorber and said condenser having a pipe connection to said condenser, a conduit leading from said boiler absorber and terminating in an inverted U-bend in said chamber, an evaporator for said liquid refrigerant, means connecting said condenser with said evaporator, whereby the

liquid refrigerant is delivered to said evaporator during the expulsion phase operation and the refrigerant evaporated in said evaporator returns to said boiler absorber during the absorption phase operation of the apparatus, a closed vessel arranged above said chamber, and a vertical pipe extending from said chamber to said vessel, whereby when the refrigerating apparatus is tilted, the liquid refrigerant in said evaporator is diverted into and collected in said vessel.

5. Absorption refrigerating apparatus of the type operating intermittently in the expulsion and absorption phases, respectively, comprising a closed system for the circulation of a refrigerant, said closed system including a boiler absorber containing dry salts capable of absorbing refrigerant vapors during the absorption phase operation of the apparatus and of driving out said vapors during the expulsion phase operation of the apparatus, a condenser for condensing the refrigerant vapors driven out during the expulsion phase operation, means connecting said boiler absorber with said condenser, an evaporator for said liquid refrigerant, means connecting said condenser with said evaporator, whereby the 20 condensed refrigerant flows to said evaporator during the expulsion phase operation and the refrigerant evaporated in said evaporator returns

to the boiler absorber during the absorption phase operation of the apparatus, and a liquid collecting trap cooperating with one of said connecting means for preventing the return of liquid refrigerant from said evaporator to said boiler absorber when the apparatus is tilted.

6. The combination with absorption refrigerating apparatus of the type operating intermittently in the expulsion and absorption phases, respectively, including at least one closed system for a refrigerant, said system consisting of at least one generator-absorber containing solid absorbent material, a condenser, and an evaporator, coupled in series, and means for heating said generator-absorber for the expulsion phase operation of said apparatus; of a chamber interposed in said closed system through which chamber the refrigerant evaporated in the evaporator passes on its way to the generator-absorber during the absorption phase operation, and the refrigerant vapors driven out of the generator-absorber during the expulsion phase operation, pass on their way to the evaporator, and means associated with said chamber for preventing the flow of liquid refrigerant from the evaporator to the generator-absorber when the apparatus is tilted from its normal position.

NILS ERLAND AF KLEEN.
